United States Patent Office.

WILLIAM BRAIDWOOD, OF MOUNT VERNON, NEW YORK.

Letters Patent No. 77,577, dated May 5, 1868.

IMPROVEMENT IN PRINTING-PRESSES.

The Schedule referred to in these Letters Patent and making part of the same.

TO ALL WHOM IT MAY CONCERN:

Be it known that I, WILLIAM BRAIDWOOD, of Mount Vernon, in the county of Westchester, and in the State of New York, have invented a new and useful Improvement in Printing-Presses; and I do hereby declare that the following is a full, clear, and exact description thereof, which will enable those skilled in the art to make and use the same, reference being had to the accompanying drawing, forming part of this specification, in which drawing—

Figure 1 is a vertical cross-section of a printing-press containing my invention.

Figure 2 is a side elevation, showing the platen and ink-roller frame down.

Figure 3 is a front elevation, taken while the parts are in the position represented in fig. 1.

Similar letters indicate corresponding parts.

All the parts of a printing-press are not represented, but only such as are necessary to enable me to fully explain my invention.

My invention relates to that class of printing-presses which has the form in a vertical position.

The letter A designates the frame of the press, in which the main shaft B has its bearings. From a pulley, C, formed on this shaft, a belt extends to and drives the large ink-distributing roller D, whose position, as in some other presses of this class, is above the place occupied by the form. The letters V V designate wheels, of considerable diameter, which are placed on the ends of shaft B, outside of the frame, from crank-pins on which wheels extend the connecting-rods J, which operate the platen, the front ends of said rods being pivoted to the ends of hubs W W formed on the edges of the platen.

The letters K K designate studs which connect the platen to the frame, and upon which studs the platen is vibrated. The ink-roller frame F is arranged to move vertically in the frame A in grooves, in whose sides it is guided in the usual manner.

The ink-rollers G are, in this example, three in number, but I do not restrict myself to this number, as the number may be increased or diminished, according to the size of the press, or character of the work that is being printed. Over the main ink-distributing roller D, and in contact therewith, I arrange the supplementary distributing-roller E, placing it in such a position that the same vertical line is tangential to the front side of each of said rollers. The usual vibrating-roller is not here shown.

The upper roller, E, is allowed to rest upon the larger roller, so as to be rotated from its contact therewith, whereby the ink-distributing surface is greatly increased, and the ink-rollers G are supplied with ink, notwithstanding more than two such rollers are placed in the frame F. When it is desired to increase the distributing-surface, I place an additional distributing-roller above the roller E, and in consequence thereof I am able to use additional rollers G, one or more, in the ink-roller frame F.

The ink-roller frame F is operated and moved up and down in its guides by means of the rigid arms H H, which are pivoted or otherwise suitably connected to the upper part of said frame F, and to the upper part of the platen. By means of this arrangement, the inking-frame is made to ascend and descend by a positive movement with the vibrations of the platen, whose upward movement towards the form causes the frame F to rise to the distributing-rollers D E, and whose downward movement causes the said frame to descend to the form.

The fingers that compose the frisket L project upwards from the rock-shaft M, whose bearings are below the inner face of the platen.

One end of said shaft M has a right-angled projection or arm, N, on whose extremity is a roller-pin that is fitted to roll in the groove of the stationary cam O, which consists, in this example, of a slotted arm that extends towards the left from one side of the frame A.

The said cam is so timed as to open and close the frisket automatically through the movements of the platen, so as to hold and release the sheet to be printed at the proper times.

The card-drop P is an arm that projects upwards from the rock-shaft Q, which has its bearings on the arms of the platen below the frisket-shaft M. On the right-hand end of said shaft Q, (observing fig. 3,) is placed a

right-angled arm, R, which extends both forwards and backwards from the line of the shaft, its forward portion being weighted, as seen at X, in order to keep the card-drop P against the platen, and its rear portion having a pin which projects horizontally from it, as shown in all the figures, which pin comes beneath the adjacent end of a tappet-lever, S, whose rear end is acted upon by a cam, U, formed on the periphery of the adjacent wheel V. The tappet-lever S is pivoted to the frame of the press at T, and it is so weighted or balanced as to return after the cam U has passed by to its normal position, its weighted end resting on pin Y.

When the lever S is vibrated by the said cam U, its forward end depresses that part of arm R with which it is in contact, and, by vibrating said arm, rocks the shaft Q sufficiently to move the card-drop P a little distance from the platen, and thereby let the card, which had been supported on its edge on the top of said drop, fall thence between the drop and platen to the ground. This motion is so timed by a proper arrangement of the cam U, and lever S, and arm R, as to take place just as the platen begins its movement away from the form after making an impression.

The several parts that compose my press are so constructed and arranged as to allow the motion of the shaft B to be reversed without any interference with the regularity of its operations, the only change required being to lengthen the lever S, as shown in red, at S' in fig. 1, so that its left-hand end will strike against the weighted part X of the arm R from below, so as to raise it and rock the shaft Q, the pin Y at the same time being removed from its present position and placed on the other side of the pivot or centre T.

The fingers of the frisket are, in practice, removed from shaft M when the card-drop is to be used, and *vice versa*. The bed, on which or against which the form is placed, is shown in red, and swung down out of its place in fig. 1 for the purpose of better exhibiting the contiguous parts of the press.

I disclaim the inventions patented to J. H. Utter, October 20, 1857, and S. A. Adams, March 8, 1853.

What I claim as new, and desire to secure by Letters Patent, is—

1. The arrangement and combination, with the card-drop P, of the cam U, lever S, and weighted arm R, substantially as described.

2. I also claim the supplementary roller E, lying on roller D, and so arranged therewith that their peripheries on the side towards the roller-frame F are in the same vertical tangential line, in combination with the vertically-moving roller-frame F, substantially as described and shown.

WM. BRAIDWOOD.
